CLAIM

The ornamental design for a neurological tool for testing nerve sensitivity, as shown and described.

DESCRIPTION

FIG. 1 is a front view of a neurological tool for testing nerve sensitivity, with the wheel guard closed, showing the new design;

FIG. 2 is a right side view of a neurological tool for testing nerve sensitivity showing the new design;

FIG. 3 is a back view of a neurological tool for testing nerve sensitivity showing the new design;

FIG. 4 is a left side view of a neurological tool for testing nerve sensitivity showing the new design;

FIG. 5 is a top view of a neurological tool for testing nerve sensitivity showing the new design;

FIG. 6 is a bottom view of a neurological tool for testing nerve sensitivity showing the new design;

FIG. 7 is a front view of a neurological tool for testing nerve sensitivity, with the wheel guard open, showing the new design; and,

FIG. 8 is a perspective view of a neurological tool for testing nerve sensitivity showing the new design.
